UNITED STATES PATENT OFFICE.

MAURICE OESTREICHER, OF NEW YORK, N. Y.

DESIGN FOR AN ARTICLE OF MANUFACTURE.

• 54,559.

Specification for Design.

Patented Mar. 2, 1920.

Application filed October 3, 1919. Serial No. 328,294. Term of patent 7 years.

To all whom it may concern:

Be it known that I, MAURICE OESTREICHER, a citizen of Hungary, and a resident of the city of New York, borough of Manhattan, in the county and State of New York, United States of America, have invented a new, original, and ornamental Design for an Article of Manufacture, of which the following is a specification, reference being had to the accompanying drawing, forming part thereof, in which the figure is a front view of a table cover embodying my new design.

The design can be applied in numerous other articles such for example as a scarf, the cover of a sofa cushion, or the like, entering into a dining room set.

I claim:

The ornamental design for an article of manufacture, as shown.

MAURICE OESTREICHER.
